CLAIM

The ornamental design for a salad bar, substantially as shown and described.

DESCRIPTION

FIG. 1 is a perspective view of a salad bar showing my new design;

FIG. 2 is a front elevational view, the opposite side being a mirror image thereof;

FIG. 3 is an end elevational view, the opposite end being a mirror image thereof;

FIG. 4 is a top plan view thereof; and

FIG. 5 is a perspective view with the cover in closed position.
